United States Patent Office.

JEAN ELIE RICHARD, OF COLUMBIA, SOUTH CAROLINA.

Letters Patent No. 93,835, dated August 17, 1869.

APPARATUS FOR PRINTING PHOTOGRAPHIC VIGNETTES.

The Schedule referred to in these Letters Patent and making part of the same.

To all whom it may concern:

Be it known that I, JEAN ELIE RICHARD, of Columbia, in the district of Richland, and State of South Carolina, have invented a new and improved Apparatus for Printing Vignettes; and I do hereby declare that the following is a full, clear, and exact description of the construction and operation of the same, reference being had to the accompanying drawings, making a part of this specification, in which—

Figure 1 is a front elevation;

Figures 2, 3, and 4, detached views of different parts;

Figure 5, a plan view of the box and stand; and

Figure 6 is a section, through line xx of fig. 1.

This invention has relation to printing large vignettes from the solar camera.

In order to print large vignettes, it is necessary that the prepared paper or blank should be placed at a distance from the camera varying according to the diverging power of the lens and the size of the picture required. And in order to form vignettes or pictures without a definite border, it is requisite that there should be, between the blank and the camera, a device for producing the peculiar shaded cloudiness that forms the background of vignettes, darkest at the outlines of the picture proper, and thence softened away into the natural color of the paper.

Such a device usually consists of a curtain of cloth or paper, painted black on the side toward the blank, with an opening through the centre for the transmission of the rays of light from the camera, and such a curtain I employ in my present apparatus.

Then, to produce the shading around the picture, the curtain has to be moved to and fro, and up and down, in order to intercept the light, for a portion of the time required to perform the operation, from the outer parts of the vignette.

There is at the present time apparatus for automatically producing such reciprocating motion in the case of "contact"-printing, that is, printing upon paper applied closely to the negative; but so far as I am aware, the only method heretofore employed for giving the required motion to a curtain placed at a distance, both from the negative and the paper, is to place an operator holding the curtain in his hand at the proper point, and cause him to give the curtain the requisite movement as nearly as he can.

As the printing of a large-sized vignette occupies from four to six hours, and as this manual operation is very tedious, and often painful to the operator, as well as expensive, it is obvious that some means of automatically imparting the necessary motion to the curtain, in the printing of large-sized vignettes from the solar camera, is a desideratum.

My invention consists in the provision of such means,

the same being the attachment of the curtain, by adjustable levers, to clock-work, in such a manner that precisely the proper motion may be automatically imparted to the curtain, including the moving of the curtain both laterally and vertically at the same time, or only vertically, or more or less laterally, as may be required, the aperture in the curtain being also provided with wings of various shapes for the purpose of giving such form to the shading as may be desired, and the whole apparatus being placed within a box having tubes running through the sides, for the passage of the light, said box being also provided with means for setting it at a greater or less altitude, at pleasure, from the stand, in order to accommodate it to the height of the camera that may be used.

In the drawings—

A is a curtain, of the kind before referred to, having an oval aperture, a , through it, and being set in an annular frame, a' , placed just outside the mouth of the tube B, passed through the side of the box that is to be placed next the camera.

The ring a' is provided with sockets a'' , &c., to hold the curtain, and a button, a''' , at the top.

At each side of the aperture are wings b , b , pivoted at their upper ends, and used to close the aperture, more or less, either on one or both sides, according as it may be wished to throw more shading on one side than the other of the picture.

The annular frame is suspended upon two pivots, c , c' , the upper one, c , of which proceeds from the end of a tongue, c'' , that is pivoted at its other end to one of the spokes of a wheel, c''' , as shown in fig. 2.

Enclosing the tongue c'' between itself and the wheel, is a convex plate, c'''' , fastened to the wheel by means of buttons d , d , so as to be easily detached, when necessary.

The convex plate has a slot, d , in it, of a regular curved shape, through which passes the pivot c .

The plate c'''' is capable of being moved upon its axis, which is also the axis of the wheel c''' , and when thus moved it changes the position of the pin c , the upper pivot of the annular curtain-frame, with reference to the axis of the wheel c''' , moving it either toward or away from said axis, and thus regulating the movement of the curtain A from side to side and up and down.

It is this movement of the curtain, as before stated, which produces the shading in the background of the picture.

As it is often desired to produce a shading that shall be of uniform width all around the picture, it is necessary, to this end, that the curtain shall move up as much as down, and to the right hand as much as to the left.

The only source of motion, however, to the curtain, is the upper pin c , as it revolves about the axis of the

wheel c'' . It is necessary, therefore, that the exact movement of the upper pivot should be imparted to the lower one. This is accomplished by a system of levers $e e'$, pivoted to the side of the box containing the whole apparatus, the upper lever e having a slot, e' , made longitudinally of its lower half, and the lower lever e' having on its upper half a sliding stud, e'' , which plays in the slot e' , and connects the two levers.

The upper end of the lever e is joined with the upper pivot c by a connecting-rod, h , and the lower end of the lever e' is joined with the pivot c' by a connecting-rod, h' , and thus, by the counter-action of the levers $e e'$, the two pivots c and c' pass through the same lateral motion at the same time; the two pivots moving, as it were, in parallel lines, the lower pivot being movable by reason of its being the end of a long elastic pin.

The lateral movements of the pivots being thus uniform, their upward ones must be so as a matter of course, and the conditions requisite for a uniform shading are perceived to be attained.

When it is desired that the shading shall be narrow, the upper pin is to be set as near the axis of the wheel c'' as possible.

On the other hand, if the shading is to be the widest possible, the upper pivot must be placed at the extreme outer end of the curved slot d . The shading will be softer in proportion as it is wider.

A result often required is that the shading shall be laid on more at the upper part of the picture than the lower. This is effected by moving the connecting-stud e'' up in the slot e' , which may be done by means of the spring x and serrations on the side of the lever e' . If it be moved up so far as to be at the same altitude with the centre of motion of the lever e , it is plain that no movement at all will be imparted to the lever e' , and that the pivot c' will be stationary, except as to its vertical motion, and only the upper part of the curtain will receive any lateral play.

The connecting-stud may be set at any point from the centre of motion of the upper lever downward, according to the excess of shading to be given to the upper part of the picture.

Again, another requirement may be that the shading shall preponderate in the lower part of the picture. To bring about this effect, the connecting-stud e'' is to be lowered in the slot e' , and the further it is lowered beyond the centre of the slot, the more will the lateral movement of the lower part of the curtain be greater than that of the upper part.

The least possible motion of the upper part, as before stated, is brought about by moving the pivot c to the inner end of the circular slot.

The weight of the annular frame and curtain, and half the weight of the connecting-rods, might be sustained by the upper pivot c , and ultimately upon the axle of the wheel c'' . In that case it would be necessary that this weight be entirely removed. I therefore attach a pea, i , to one end of a scale-beam, k , pivoted in the upper right-hand corner of the box C .

A rod, k' , connects the opposite end of the scale-beam with the upper part of the annular frame a' .

The pea i is of equal weight with the load that would otherwise be sustained by the pivot c , and it not only relieves the axle of the wheel c'' of a considerable amount of friction, but it enables the system of clock-work, by means of which the wheel c'' is rotated, to impart to it a regular and uniform motion.

I design to attach hands and a dial to the clock-work, and thus combine in one instrument a printing-apparatus and a clock.

From a consideration of the manner in which the pivot c is connected with the slotted plate c''' , it is obvious that the pivot cannot move of itself in the slot, inasmuch as the tongue c'' prevents the pivot from

moving lengthwise of the slot, and the sides of the latter prevent the pivot from moving sidewise.

The box C , in which my apparatus is enclosed, is furnished, at its edges, with longitudinal guide-ways l l' , or with their equivalents, grooves sunk in the edges, and the guide-ways enclose standards l , which project vertically upward from a platform, l'' , on which the box rests, between the standards.

The box may be set at any desired height in the standards, and, when raised to the proper elevation, it is to be fixed by means of spring-plates m , which are bent into prongs m' at their tops and bottoms, the upper prongs resting on the tops of the standards l , and the lower prongs in grooves m'' , of proper dimensions, made longitudinally of the standards on the inside.

Recesses are made in the inside of the standards for the reception of the spring-plates.

When the lower prongs of the latter rest on the bottoms of the grooves m'' , the curvature of the spring-plates clamps the box C in the standards.

When the spring-plates are raised so that their lower prongs strike the tops of the grooves m'' , the curved parts of the plates are out of the guide-ways, and the box may slide freely up and down.

This arrangement furnishes me with means for easily fixing the box at any required height in the standards to suit the camera, and also for readily changing its position.

The tubes B and D , passing through the front and back sides of the box, have slides $B' D'$, for closing them, when not required for the transmission of light.

The lower pivot-pin c' has a small transverse groove running round it, near its outer end, so that there is a head on its extreme outer end, and a shoulder on the other side of the groove, and in the groove and between the head and shoulder, is supported the projection a' of the annular frame a' , in such a manner, that whatever the position the box may be placed in, the whole lower part of the apparatus is sustained upon the pin.

Having thus described my invention,

What I claim as new, and desire to secure by Letters Patent, is—

1. The box C , for enclosing and protecting the within-described apparatus, provided with tubes B and D , for the transmission of light, and with slides $B' D'$, as and for the purpose set forth.

2. The combination of an apparatus for printing photographs, with a clock, when the same mechanism operates both the clock and the printing-apparatus, substantially as described.

3. The combination of the slotted plate c''' with the tongue c'' , provided with the pivot c and wheel c'' , all arranged and operating in the manner set forth.

4. The combination of the lever e , furnished with the slot e' , with the serrated lever e' , provided with the sliding stud e'' and spring-plate x , arranged and operating substantially as described.

5. The combination of the levers $e e'$, connecting-rods $h h'$, annular frame a' , all arranged and operating as explained.

6. The annular frame a' , provided with the sockets a'' and button a''' , substantially as described.

7. The combination of the curtain A with the wings b , as and for the purpose specified.

8. The combination of the scale-beam k , counter-weight i , annular frame a' , and connecting-rods $h h'$, all arranged and operating substantially as described.

9. The spring-plate m , provided with the prongs m' , in combination with the grooved standard l'' and box C , as and for the purpose specified.
